United States Patent Office

Des. 196,673
Patented Oct. 22, 1963

196,673

AUTOMOBILE THERMOMETER

William E. Chisham, Jr., 4860 Jumano St.,
San Diego, Calif.

Filed Jan. 28, 1963, Ser. No. 73,332

Term of patent 14 years

(Cl. D52—7)

Fig. 1

Fig. 2

Fig. 3

Fig. 4

FIGURE 1 is a perspective view of an automobile thermometer, showing my new design;

FIGURE 2 is a side elevational view thereof, as taken from the left side of FIGURE 1;

FIGURE 3 is a rear elevational view thereof; and

FIGURE 4 is a top plan view thereof.

I claim:

The ornamental design for an automobile thermometer, as shown.
